UNITED STATES PATENT OFFICE.

HOWARD M. BARBER, OF STONINGTON, CONNECTICUT, ASSIGNOR TO C. B. COTTRELL & SONS COMPANY, OF NEW YORK, N. Y., A CORPORATION OF DELAWARE.

SHEET COLLECTING, ASSOCIATING, AND FOLDING MACHINE.

1,269,041.

Specification of Letters Patent.

Patented June 11, 1918.

Application filed August 5, 1916. Serial No. 113,369.

To all whom it may concern:

Be it known that I, HOWARD M. BARBER, a citizen of the United States, and resident of Stonington, in the county of New London 5 and State of Connecticut, have invented a new and useful Improvement in Sheet Collecting, Associating, and Folding Machines, of which the following is a specification.

The object of this invention is to provide 10 novel means for associating extra sheets fed from different sources of sheet supply, such, for instance, as cover and insert sheets, with a collected group of sheets fed from another 15 source of supply, means preferably being employed for stitching the so associated sheets together for folding the same.

My invention more particularly includes 20 a rotary sheet associating carrier, a rotary sheet collecting carrier arranged to transfer groups of sheets to the associating carrier, and rotary sheet carriers each arranged to transfer a sheet from a source of extra sheet supply to the associating carrier whereby the collected group of sheets and the sheets 25 from the different sources of sheet supply are combined on the associating carrier.

A practical embodiment of my invention is represented in the accompanying drawings, in which

30 Figure 1 represents a detail longitudinal vertical central section through so much of a sheet collecting, associating and folding machine, as includes my invention,

Fig. 2 represents a similar section taken 35 just inside the near side frame,

Fig. 3 represents a similar section taken just inside the far side frame, and

Fig. 4 is a similar section taken just outside the far side frame, showing the geared 40 connection between the several parts.

1 designates a source of extra sheet supply, such, for instance, as an insert sheet supply. 2 designates a different source of extra sheet supply, such, for instance, as a 45 cover sheet supply. These sources 1 and 2 are herein shown as feed tables, the table 1 being provided with a movable sheet stop 3 and the table 2 with a movable sheet stop 4.

Rotary cutters 5, 6, mounted on suitable 50 shafts 7, 8, are arranged to cut a single web or a plurality of superimposed webs which pass between the rolls 9, 10, into sheets, which sheets are passed downwardly between the guides 11, 12, to a three way collecting rotary carrier 13, mounted on a shaft

14, which carrier, in the present instance, is shown as being provided with three sets of grippers 15. Tucking disks 16, mounted on the shaft 17, serve to insure the engagement of the advance edges of the sheets by 60 the grippers 15.

The rotary sheet associating carrier 18, mounted on the shaft 19, is herein shown as having three sets of grippers 20. A rotary sheet transfer carrier 21 mounted on the 65 shaft 22 is provided with a set of grippers 23 arranged to feed an extra sheet as, for instance, an insert sheet, from the source of extra sheet supply 1 to the grippers 20 on the rotary sheet associating carrier 18. A 70 rotary sheet transfer cylinder 24, mounted on the shaft 25, is provided with a set of grippers 26 arranged to feed a sheet, such, for instance, as a cover sheet, from the source of extra sheet supply 2 to the grippers 75 20 on the sheet associating carrier 18.

A stitcher table 27 is arranged to receive the associated sheets, on which table the sheets are stitched transversely of their travel by the coacting parts 28, 29, of two or 80 more stitchers. A movable stop 30 is located at the outer end of the stitcher table 27 in position to engage the advance edges of the associated sheets and hold them momentarily in position for the stitching operation. 85

Coacting rotary carriers 31, 32, mounted on their respective shafts 33, 34, are provided, the carrier 31 having a set of grippers 35 arranged to take the stitched associated sheets from the stitcher table 27 and also having a folding blade 36 arranged to coat with the folding jaws 37 on the rotary carrier 32 for imparting a transverse fold to the associated sheets along their transversely stitched line. 95

Endless carriers 38, 39, serve to carry the associated sheets onto and off from the stitcher table 27 and endless carriers 40, 41, are arranged to carry the product from the rotary carrier 32 to a suitable delivery 42, 43. 100

The train of gears, designated by 44 to 71 inclusive, is operative to drive the parts at the proper relative speeds.

A switch 72 is located at the entrance end of the stitcher table 27, which switch is operated from a cam 73 on the shaft 33 of the rotary carrier 31 through the connection 74. 105

A fixed cam 75 opens the grippers 15 successively at their sheet receiving point. Movable cams 76, 77, open the grippers 20 110

and 15, every two-thirds of a revolution of the rotary carriers 18 and 13 to transfer a group of sheets from the carrier 13 to the carrier 18. These movable cams 76, 77, are 5 operated from the rotary cam 78, on the shaft 79, through the connection 80. A movable cam 81 operated from the rotary cam 82 on the shaft 22 through the connection 83, is arranged to open alternate grippers 20 on the associating carrier 18 to receive a sheet, as, for instance, an insert sheet, fed from the source of extra sheet supply 1 by the rotary carrier 21.

10 A movable cam 84 operated from the rotary cam 85 on the shaft 25 through the connection 86 is arranged to open alternate grippers 20 to receive an extra sheet, as, for instance, a cover sheet fed from the source 2 of extra sheet supply, by the rotary carrier 24.

15 A fixed cam 87 is arranged in position to open the grippers 23 to transfer the extra sheet therefrom to alternate grippers 20 on the associating carrier 18 every revolution of the carrier 21. A fixed cam 88 is arranged 20 in position to open the grippers 26 to transfer a sheet to alternate grippers 20 on the associating carrier 18 every revolution of the rotary carrier 24.

25 30 A movable cam 89 operated by the rotary cam 90 on the shaft 22 through the connection 91, is arranged to open alternate grippers 20 on the associating carrier 18 to release the associate group of sheets and extra 35 sheets from the different sources of supply to permit the so associated sheets to be fed onto the stitcher table 27.

35 The grippers 23 are tumbler operated for taking the sheets from the source of sheet supply 1, the tumbler 92 being controlled by the pins 93, 94. The grippers 26 are also tumbler operated to take the sheets from the different source of sheet supply 2, their tumbler 95 being controlled by the pins 96, 97. 40 45 The movable sheet stop 3 is controlled by the cam 98 which is arranged to engage the stop roller 99.

50 The movable sheet stop 4 is controlled by the cam 100 which is arranged to engage the sheet stop roller 101.

55 The sheet stop 30 is controlled by the cam 102 which is arranged to engage the sheet stop roller 103.

The set of grippers 35 on the rotary carrier 31 is tumbler operated to take the sheets from the stitcher table 27, the tumbler 104 being controlled by pins 105, 106.

60 65 The coacting folding mechanism on the rotary carriers 31, 32, is of the well known floating blade and jaw type, the operation of the blade 36 being controlled by the cam 107 and the operation of the jaws 37 being controlled by the cams 108, 109, 110.

70 75 A fixed cam 111 is arranged to open the grippers 35 at the time of folding.

Positively driven rollers 112, 113, bear against the surface of the rotary carrier 18 and positively driven rollers 114, 115, bear against the surfaces of the rotary carriers 21, 24, for holding the sheets in register on their 70 respective surfaces when their grippers are opened.

In operation the rolls 9, 10, are arranged to feed one or more webs to the rotary cutters, 5, 6, the collected sheets are severed 75 from the web or webs, and fed through the guides 11, 12, to the collecting carrier 13. The carrier is herein shown as being arranged to collect two sheets or groups of superimposed sheets and transfer the same 80 to the associating carrier 18 on top of an extra sheet, as, for instance, an insert sheet fed from the source of sheet supply 1 to the associating carrier 18 by the rotary carrier 21.

85 The rotary carrier 24 is arranged to transfer a sheet, as, for instance, a cover sheet, from the source of extra sheet supply 2 to the associating carrier 18 on top of the group of sheets. The so associated sheets 90 are then fed onto the stitcher table 27, the switch 72 being depressed to insure the passage of the so associated sheets onto the table. These associated sheets are fed against the stop 30 and while held momentarily thereby, the sheets are stitched transversely of their travel. The sheets are then released by the stop 30 and their advance edges are taken by the grippers 35 of the rotary carrier 31. The sheets are then folded 95 off transversely of their travel along their stitched line onto the rotary carrier 32 and from thence they are fed by endless carriers 40, 41, to the delivery 42, 43.

100 105 From the above description it will be seen that the sheets from the different sources of extra sheet supply are fed to the same side of the associating carrier at different points thereon and that the group of sheets are fed to the associating carrier at still 110 another point, the associating carrier being arranged to first take an extra sheet as, for instance, an insert sheet, then take a group of sheets on top of the insert sheet, and finally take another extra sheet, as, for instance, a cover sheet, on top of the group of sheets and feed the same to the stitcher table. This makes a very simple and effective arrangement.

115 120 It is obvious that the rotary carrier 13 can collect a group of single sheets or a group of superimposed sheets and it is also obvious that the extra carriers 21 and 24 may feed one or more sheets from their respective sources of extra sheet supply, 125 without departing from the spirit and scope of my invention.

130 It is evident that changes may be resorted to in the form, construction and arrangement of the several parts without departing

from the spirit and scope of my invention; hence I do not wish to limit myself strictly to the structure herein shown and described, but

5 5. What I claim is:

1. Means for collecting a group of sheets, a rotary carrier arranged to associate thereon extra sheets fed from different sources, with said group of sheets, separate rotary carriers arranged to feed the extra sheets to the associating carrier, and means for stitching the so associated sheets together and delivering the same.

10 2. Means for collecting a group of sheets, a rotary carrier arranged to associate thereon extra sheets fed from different sources, with said group of sheets, separate rotary carriers arranged to feed the extra sheets to the associating carrier, and means for stitching and folding the so associated sheets together and delivering the same.

15 3. Means for collecting a group of sheets, a rotary carrier arranged to associate thereon first an extra sheet from one source, then the group of sheets, and, finally, an extra sheet from another source, separate rotary carriers for feeding the extra sheets to the associating carrier, and means for stitching the so associated sheets together and delivering the same.

20 4. Means for collecting a group of sheets, a rotary carrier arranged to associate thereon first an extra sheet from one source, then the group of sheets, and, finally, an extra sheet from another source, separate rotary carriers for feeding the extra sheets to the associating carrier, and means for stitching and folding the so associated sheets together and delivering the same.

25 5. A rotary carrier arranged to collect thereon a group of sheets, a rotary carrier arranged to associate thereon extra sheets fed from different sources and the group of sheets fed from their collecting carrier, rotary carriers arranged to feed the extra sheets from different sources to the associating carrier, and means for stitching the so associated sheets together and delivering the same.

30 6. A rotary carrier arranged to collect thereon a group of sheets, a rotary carrier arranged to associate thereon extra sheets fed from different sources and the group of sheets fed from their collecting carrier, rotary carriers arranged to feed the extra sheets from different sources to the associating carrier, and means for stitching and folding the so associated sheets together and delivering the same.

35 7. A source of main sheet supply, a rotary associating carrier, different sources of extra sheet supply, means for collecting a group of main sheets and feeding them to the associating carrier, separate means each ar-

source of extra sheet supply and feed it to the associating carrier to be combined thereon with the said group of main sheets, and means for stitching the so associated sheets together and delivering the same. 70

8. A source of main sheet supply, a rotary associating carrier, different sources of extra sheet supply, means for collecting a group of main sheets and feeding them to the associating carrier, separate means each arranged to take a sheet from its respective source of extra sheet supply and feed it to the associating carrier to be combined thereon with the said group of main sheets, and means for stitching and folding the so associated sheets together and delivering the same. 75

9. A source of main sheet supply, a rotary associating carrier, different sources of extra sheet supply, means for collecting a group of main sheets and feeding them to the associating carrier, separate rotary carriers each arranged to take a sheet from its respective source of extra sheet supply and feed it to the associating carrier to be combined thereon with the said group of main sheets, and means for stitching the so associated sheets together and delivering the same. 80

10. A source of main sheet supply, a rotary associating carrier, different sources of extra sheet supply, means for collecting a group of main sheets and feeding them to the associating carrier, separate rotary carriers each arranged to take a sheet from its respective source of extra sheet supply and feed it to the associating carrier to be combined thereon with the said group of main sheets, and means for stitching and folding the so associated sheets together and delivering the same. 90

11. Means for collecting a group of sheets, a rotary associating carrier for combining thereon sheets fed from different sources of extra sheet supply with the group of sheets, separate means for feeding the extra sheets to the same side of the associating carrier, and means for stitching the so associated sheets together and delivering the same. 110

12. Means for collecting a group of sheets, a rotary associating carrier for combining thereon sheets fed from different sources of extra sheet supply with the group of sheets, separate means for feeding the extra sheets to the same side of the associating carrier, and means for stitching and folding the so associated sheets together and delivering the same. 115

13. Means for collecting a group of sheets, a rotary associating carrier for combining thereon sheets fed from different sources of extra sheet supply with the group of sheets, separate rotary carriers for feeding the extra sheets to the same side of the associating carrier, and means for stitching the 120

130

so associated sheets together and delivering the same.

14. Means for collecting a group of sheets, a rotary associating carrier for combining thereon sheets fed from different sources of extra sheet supply with the group of sheets, separate rotary carriers for feeding the extra sheets to the same side of the asso-

ciating carrier, and means for stitching and folding the so associated sheets together and delivering the same.

In testimony that I claim the foregoing as my invention, I have signed my name this third day of August, 1916.

HOWARD M. BARBER.
